WEB TENSIONING DEVICE

Paul A. Sperry, New Haven, Conn.

Application May 9, 1952, Serial No. 286,935

8 Claims. (Cl. 26—63)

1

This invention relates to a web tensioning device for tensioning a web of material such as fabric or paper transversely, or differentially tensioning the web longitudinally, or both, by means of one or more web engaging rolls of variable longitudinal curvature.

Longitudinally curved rolls of the general type to which this invention relates are now well-known in the textile industry and have been employed heretofore as expanders for the purpose of tensioning a fabric web transversely or removing the wrinkles therefrom as the web travels between various textile processing stages. Combinations of these longitudinally curved rolls have also been used as bow correcting devices to apply tension to various portions of a fabric web for the purpose of correcting the bowed condition of the weft or filler threads. While the curvature of these presently used rolls may vary as between individual rolls for different uses, to the best of my knowledge all are formed with a predetermined curvature which is thereafter permanent and non-variable, during the operation of the apparatus.

The fixed curvature of the prior expander or bow correcting rolls introduces a number of problems into their use which are not easily overcome. For example, in bow correcting, a roll of the proper curvature for one kind of fabric may not be at all suitable for another kind of fabric. The same may be true in fabric stretching and wrinkle or crease removal. In addition, a given web of the same fabric may vary in characteristics over its length due to unequal shrinkage or stretching, and thus a roll which may be adequate to properly tension one portion of the web may be quite inadequate for another portion. To overcome these problems, the rolls used with the processing apparatus must be interchanged often to insure that rolls of the proper curvature are being used, and where combinations of rolls are employed the combination must be adjusted frequently to obtain the desired result. This manipulation and adjustment necessarily entails many work stoppages resulting in a considerable loss of production time and man-hours, and consequently the overall efficiency of the processing operations is drastically reduced.

The principal purpose of my invention therefore is to overcome many of the problems connected with the expander and bow correcting devices now in use by providing a web tensioning device wherein the longitudinal curvature of the individual web engaging rolls may be varied by manual or automatic means to obtain the de-

2

sired arcuate curvature of the roll. Since the radius of curvature of the rolls or rolls can be varied, it will be apparent that a single device can be used in processing any type of web by making the proper adjustment for the given material and desired operation. Furthermore, the radius of curvature can be adjusted while the device is in operation so that compensation for variations within a particular web can easily be made without stopping the travel of the web. The device of the invention, hereinafter described in detail, can be used in connection with most textile processing operations but is not confined to fabric processing since its ready adaptability permits its use in the processing of other types of webs such as webs of paper, rubberized material or plastic.

With the foregoing and other considerations in view, it is a primary object of my invention to provide a web tensioning device having web engaging rolls of variable longitudinal curvature.

Another important object of my invention is to provide a web tensioning device wherein the radius of curvature of the web engaging rolls is variable between relatively wide limits.

A further important object of the invention is to provide a web tensioning device wherein the radius of curvature of the web engaging rolls can be quickly and easily varied by manual or automatic means while the device is in operation.

Other objects and advantages of the invention will become apparent from the following detailed description read in conjunction with the accompanying drawings and from the appended claims. The accompanying drawings, in which like reference numerals are used to designate similar parts throughout, illustrate one practical embodiment for the purpose of disclosing the invention. The drawings, however, should not be taken in a limiting or restrictive sense since it will be apparent to those skilled in the art that various changes in the illustrated construction may be resorted to without in any way departing from the concept of the invention.

In the drawings:

Figure 1 illustrates an elevation of one practical embodiment of the device of the invention;

Figure 2 illustrates an elevation partly in section of the web engaging roll of the device of Figure 1;

Figure 3 illustrates a cross-section through the roll taken along line 3—3 of Figure 1;

Figure 4 illustrates a section through the roll taken along the line 4—4 of Figure 3;

Figure 5 illustrates a cross-section through a modified form of roll;

Figure 6 illustrates a section through a modified form of roll bearing; and

Figure 7 illustrates an end view of the modified bearing of Figure 6.

Referring now to the drawings, a web tensioning device with a single web engaging roll 10 is shown in Figure 1. Roll 10, which may be used as an expander to transversely tension a web or as a bow correcting device or for any other similar purpose, is comprised of a central, resilient bar or axle 12, a plurality of ball or roller bearings 14, and an outer flexible sleeve 16, as will hereinafter be more fully described. The bar 12 is formed with slightly enlarged extremities 18 and 20, each extremity having a smooth bore therethrough to respectively receive one of a pair of lever arms 22, 24. The bar is non-rotatably secured to arms 22, 24 as at the approximate mid-points thereof by some means such as lock nuts 26 threaded on the arms.

One extremity of each of the lever arms 22, 24 is adapted to be pivotally secured as at 28 and 30 to a supporting means 32 which may be a frame of the processing equipment or a separate base member or a pair of fixed members. The opposite extremities of arms 22, 24 carry a pair of collar members 34, 36 which are respectively pivoted on the arms. Collars 34, 36 are oppositely threaded to receive the right and left-hand screw threads respectively of a connecting rod 38, as shown. Since the threaded connections between rod 38 and each of the arms 22, 24 are oppositely arranged, rotation of the rod in one direction will cause the arms to converge while rotation of the rod in the opposite direction will cause the arms to diverge. The bar 12 is formed with a predetermined arcuate curvature or set but has sufficient resiliency so that this curvature can be substantially varied within the elastic limit of the bar. Since the bar ends 18, 20 are rigidly secured to arms 22, 24, any convergent or divergent movement of the arms will vary the radius of curvature of the bar, and consequently of the roll 10. The approximate degree of permanent curvature or set with which bar 12 may be formed is illustrated in Figure 1, and with this degree of curvature arms 22, 24 will be slightly convergent as shown. If rod 38 is now turned to cause arms 22, 24 to converge more sharply, the curvature of bar 12 and roll 10 will be increased. For example, if arms 22, 24 are moved to the positions indicated by phantom lines 40, the bar and roll will be forced into an approximately circular arc of smaller radius as indicated by the dash lines 42. Conversely, if rod 38 is turned to cause arms 22, 24 to diverge from their phantom line positions, the curvature of bar 12 and roll 10 will be decreased. In this manner, the longitudinal curvature of the bar and roll can be varied at will within the elastic limit of the bar. Connecting rod 38 may be actuated to vary the curvature of roll 10 by manual means such as a hand wheel 44, or by some suitable power means such as a reversible electric motor, an air operated motor, or a hydraulic motor.

The roll 10 must be able to rotate freely upon the fixed bar 12 so that it can be driven by the travelling web. To this end, a series of roller bearings 14 or similar elements are mounted on bar 12, and a flexible sleeve 16 is fitted over the outer races 46 of the bearings as is best shown in Figures 2 and 3. The flexible sleeve 16 may be of rubber or some other material which will afford sufficient traction by the web on the roll

so that objectionable slippage is prevented. The roller assembly is completed by a pair of end caps 47 which serve to keep dust and dirt from the bearings. This portion of the roll 10 is substantially conventional and can be constructed in a number of suitable ways.

The rotatable portion of roll 10 must also be able to conform to any curvature assumed by the bar 12. If the bar is of cylindrical cross section, this may be accomplished as shown in Figures 3 and 4 wherein the inner diameter of the inner races 48 of the bearings is larger than the diameter of the bar so that there is sufficient clearance to allow for whatever curvature there might be in the bar. However, as shown by the modification of Figure 5, the bar 12 need not be of cylindrical cross section but may be of square, rectangular, hexagonal, octagonal or almost any other cross section. One important consideration in the choice of bar cross section is the degree of difficulty involved in forming the inner races 48 of the bearings to fit the cross section chosen. As shown in Figure 5, the bar is of rectangular cross section 50 and the inner race 48 of the bearing is formed accordingly to fit the bar.

A further modification is illustrated in Figures 6 and 7, wherein the inner race 48 of the bearing is formed with a curvilinear inner surface 52 as shown in Figure 6. This construction permits any desired amount of curvature in the bar without any binding on the bearing. Obviously, many other suitable bearing constructions will permit the same freedom of bar action.

From the foregoing description it will be apparent that I have provided a novel and very useful device for tensioning a web of any type of tensionable material. While the operation of but one web engaging roll has been illustrated, it will be understood that any desired number of rolls can be used for web stretching, wrinkle and crease removal, correcting bowed conditions in the weft or filler threads of a fabric, or for a number of other similar operations. In these operations any fabric from fine silk or rayon to heavy canvas duck may be treated by simply adjusting the web engaging roll to the proper curvature for the given material and desired operation. Non-fabrics such as paper, seamless rubber or plastic may be similarly treated. In addition, since adjustment can be easily made during operation, differential conditions of stretch or shrinkage within a particular web can be rapidly compensated for without stopping the travel of the web.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

65. What is claimed is:

1. In a device for tensioning webs, support means, a pair of lever arms each pivoted at one end on said support means, a resilient web engaging member of variable longitudinal curvature secured between said arms, and means in engagement with the free ends of said arms to simultaneously move said arms towards or away from one another thereby causing the curvature of said web engaging member to change.

70. 2. In a web tensioning device; a pair of lever

arms each adapted to be pivotally mounted at one end thereof on fixed supporting means; a resilient web engaging member of variable longitudinal curvature supported by said arms; a connecting member in threaded engagement with the opposite ends of said arms, said threaded engagement between said connecting member and said individual arms being opposite to one another; and means to selectively rotate said connecting member to simultaneously move said arms towards or away from one another and thereby vary the curvature of said web engaging member.

3. In a web tensioning device; support means; a pair of lever arms each pivoted at one end on said support means; a resilient web engaging member having adjustable longitudinal curvature and including a resilient, longitudinally curved central bar supported by said arms, a plurality of bearing members supported on said bar, and a flexible sleeve positioned over said bearing members; and means coacting with the free ends of said arms to simultaneously move said arms towards or away from one another and thereby adjust the curvature of said web engaging member.

4. An apparatus as defined in claim 3 wherein in said central bar is of circular cross section, and said bearing members include inner races whose inner diameter is larger than that of said bar.

5. An apparatus as defined in claim 3 wherein in said central bar is of circular cross section, and said bearing members include inner races whose inner surfaces are curvilinear.

6. In a web tensioning device; a base member, a pair of lever arms each pivoted at one end on said base member; a resilient web engaging roll of variable longitudinal curvature, said roll including a resilient central bar non-rotatably supported by said arms at their approximate mid-points, a plurality of bearing members mounted

on said bar, and a flexible sleeve mounted on said bearing members; a connecting rod having a right-hand threaded engagement with the free end of one of said arms and a left-hand threaded engagement with the free end of the other of said arms; and means to selectively rotate said connecting rod to simultaneously move the free ends of said arms towards or away from one another and thereby vary the curvature of said web engaging roll.

7. In a device for tensioning webs, support means, a lever arm having provision for its pivotal mounting on said support means, a resilient web engaging member of variable longitudinal curvature secured with one end to said arm remote from the pivotal mounting of the latter, means for securing the other end of said web engaging member to said support means, and means operative to swing said arm about its pivot mounting thereby causing the curvature of said web engaging member to change.

8. In a device for tensioning webs, support means, a pair of lever arms each pivotally mounted at one end on said support means, a resilient web engaging member of variable longitudinal curvature connected with its ends to said arms, respectively, remote from the pivotal mountings of the latter, and means operatively connected with said arms and operative to simultaneously move said arms toward or away from one another thereby causing the curvature of said web engaging member to change.
